UNITED STATES PATENT OFFICE.

WILLIAM P. BENDING, OF PALO ALTO, CALIFORNIA.

APPARATUS FOR DRYING OILS.

1,144,522.

Specification of Letters Patent.

Patented June 29, 1915.

Application filed September 30, 1914. Serial No. 864,381.

To all whom it may concern:

Be it known that I, WILLIAM P. BENDING, a citizen of the United States, residing at Palo Alto, in the county of Santa Clara and State of California, have invented new and useful Improvements in Apparatus for Drying Oils, of which the following is a specification.

This invention relates to an apparatus for neutralizing, clarifying and drying oils, particularly oils made from California asphalt base, crude oils for lubrication or other uses, wherein the hydrocarbon oil is first treated in an agitator by the action of an acid to remove the tarry constituents, then subjected to a process whereby the acid is neutralized by an alkali and then washed to remove the alkali, and the neutralized oil finally relieved of its watery particles or all moisture adherent to it after it has been so washed.

The primary object of my invention is to provide a simple type of apparatus by which the operation of drying the oils may be carried out in a rapid, efficient and economical manner.

The invention consists of the features of construction, combination and arrangement of parts herein fully described and claimed, reference being had to the accompanying drawings in which:

Figure 1 is a side elevation, partly in section, of an oil drying apparatus embodying my invention. Fig. 2 is a top plan view of the neutralizing and washing vat. Figs. 3 and 4 are enlarged detail sections on the lines 3—3 and 4—4 of Fig. 1, particularly showing the heating means in the drying tower or stand pipe. Fig. 5 is a section on an enlarged scale through the air supplying and delivery portion of the apparatus.

Referring to the drawings, 1 designates a tank or vat employed for neutralizing and washing the oil after having been subjected to acid treatment. This vat may contain any desired number of compartments. In the present instance it is shown as provided with primary and secondary compartments 2 and 3, each having a bottom collecting chamber or basin 4 provided with a suitably closed drain outlet 5 for the removal of any saponaceous or other residue left remaining after the oil is neutralized. In the bottom of each of the said compartments 2 and 3 is a steam heating coil 6, the inlet ends of which communicate with live steam supply pipes 7

having controlling valves 8 and the outlet ends of which are controlled by valves 9 whereby the water of condensation may be discharged and the outlet ends governed for a desired circulation of the steam. If desired, the tank or vat compartments may be steam jacketed at the bottom or other heating means employed within the tank or vat compartments.

The oil to be treated is first conveyed from the acid agitator to the compartment 2, in which it is subjected to a preliminary process of neutralization, and thence transferred from the compartment 2 to the compartment 3, if desired, for a further or final step in the process of neutralization and washing, or the entire process may be carried out in either compartment, as desired. A discharge pipe 10 for the neutralized oil is provided with branches communicating with a basin 4 of the vat compartments and leads from the tank to a suitable pump 11, whereby the neutralized oil is drawn from the vat and supplied to the clarifying and drying portion of the apparatus for treatment. It will, of course, be understood that the oil treated in the vat is not only neutralized but clarified to a determined degree. In the course of further treatment in the clarifying and drying part of the apparatus, above referred to, the oil is further clarified by oxidation and the watery particles or moisture driven therefrom.

The neutralized and washed oil drawn by the pump 11 from the vat through the suction or discharge pipe 10, is forced by the pump through a delivery pipe 12 into an elevated heating chamber or casing 13, wherein a desired temperature of the oil is maintained during the clarifying and drying treatment. In this chamber or casing 13 is disposed a heating coil 14 having a valved inlet 15 designed to communicate with any suitable source of steam supply and a valve 100 outlet 16. The casing 13 is arranged at any suitable elevation within a tower or stand pipe 17 and communicates at its top and bottom with the upper and lower sections thereof. In the top of said casing is a receiving trough 18 which communicates with the pipe 12 and receives the oil therefrom, and which is provided in its bottom with an elongated contracted outlet 19 overlying the coil 14 so as to cause the oil to flow downward over the coil in direct contact therewith and to be heated to an efficient degree.

The upper portion of the stand pipe is designed to extend to the exterior of the building in which the apparatus is arranged and is provided with a hood 20 to prevent the entrance of snow or rain water, while permitting of the outflow of air and the moisture from the oil carried off thereby.

The heated oil passes from the chamber 13 by gravity down through the lower section 10 of the stand pipe 17 which is arranged to discharge the oil into a combined receiving vessel and ventilator 21 having a conical upper portion and a cylindrical lower portion, the latter communicating with the receiving portion or chamber 22 of a purified oil receiving tank 23, which also has a discharge portion or chamber 24, said chambers being separated except at their bottom portions by a partition 25, terminating sufficiently above the bottom of the tank to provide a constricted flow passage.

The ventilator 21, when open, allows air 65 from the outside to flow through said ventilator and into said stand pipe, and thence 25 to pass upward through the stand pipe and casing 13 and to finally pass outwardly through the outlet 20. It will be understood that this air is heated on its upward passage and rises and finally discharges and hence 30 induces a circulation in the stand pipe, whereby fresh air is drawn into the stand pipe through the ventilator for upward 35 movement and discharge, as before described.

35 A hood or cover 26 is, however, provided for closing said ventilator and cutting off communication between the same and the atmosphere at that point, so that when desired a current of air from a fan or blower 40 45 communicating with the compartment 22 may be supplied to the stand pipe, in the event that the natural draft or air current afforded through the open ventilator is not sufficient or the use of the ventilator is not desired.

The hood or cover 26 is slidably mounted on the stand pipe 17 and frictionally engages the same so that it will retain itself in any position of adjustment. This hood 50 or cover may be adjusted with relation to the member 21 to vary the size of the intervening air inlet, and may be moved down upon said member 21 to entirely close said inlet.

55 On its entrance into the trough 18 and downflow over the coil 14 and passage through the stand pipe to the chamber 22 of the receiving tank, the oil, which is heated to the desired degree, comes in contact with 60 the ascending current of warm air which takes up the watery particles or moisture therefrom, thus oxidizing and brightening oil or further clarifying the oil and at the same time drying or relieving the oil of its 65 watery constituents, which discharge with

the air through the stand pipe to the atmosphere. The purified oil flows from the chamber 22 into the chamber 24 through the intervening bottom constricted passage and is drawn out through a discharge pipe 28 70 by means of a pump 29, with the outlet of which may communicate one or a series of final delivery pipes 30 having controlling valves 31, by means of which the purified oil may be delivered to the storage receptacle or receptacles designed for its reception. The pipe 28 depends into the chamber 24 to a point just above the level of the passage between the chambers 22 and 24 80 formed by the baffle or partition 25, which thus provides a normally sealed trap between said chambers which prevents the passage of the air from the fan 23, when the latter is in action, into the chamber 24 when the pump 29 is in action, thus insuring the delivery of the air from the fan directly into the drying conduit or tower.

It has been necessary in the treatment of hydrocarbon lubricating and illuminating oils containing more or less tar to brighten 90 or clarify them after the removal of the tar by acid and the neutralization of the acid by alkali and to settle or expose the oil to the atmosphere for a considerable period, or say a month, until the water or 95 other volatile impurities have been separated or removed. The present invention provides an apparatus whereby the process of neutralization may not only be conveniently and rapidly effected, but by means of which the oil may be clarified and dried in a simple and inexpensive manner and within a very short period, the entire treatment requiring but a few hours, the advantages of which will be evident.

I claim:

1. An oil drying apparatus including an oil receiving tank, a baffle or partition depending from the top of said tank, and terminating above the bottom thereof and separating the tank into receiving and delivery compartments, an inlet communicating with the top of the receiving compartment of said tank, means for discharging the oil from the delivery compartment of said tank, an air supplying device communicating with the receiving compartment of the tank above the level of the lower end of said baffle or partition, a tower having its lower end disposed in spaced relation to the inlet of the oil receptacle for the supply of air independently of the said air supplying device, a ventilator comprising relatively fixed and adjustable members upon the receptacle inlet and air inlet and the end of the tower, whereby direct flow of air into the tower may be cut off or such flow of air thereto governed, a drying chamber at a point in the length of the tower, means for heating the same, means for supplying 110

oil to said chamber to be subjected to the drying action of the heat therein and the upwardly flowing column of air.

2. An oil drying apparatus including a vat having heating means therein; an oil receiving tank, a partition depending from the top of said tank and terminating above the bottom thereof and separating the tank into receiving and delivery compartments, a tower communicating at its lower end with the receiving compartment of the receiving tank, means for circulating air upwardly through the tower, an oil heating

and receiving chamber within the tower, oil feeding means between the vat and chamber, a delivery pipe communicating with the delivery compartment of the receiving chamber; and a delivery pump connected with said pipe.

In testimony whereof I affix my signature in presence of two witnesses.

WILLIAM P. BENDING.
